TOY PISTOL OR SIMILAR ARTICLE

Rubin Reif, Fayetteville, Ark., assignor to American Arts
& Crafts, Inc., Columbus, Ohio, a corporation of Ohio

Application January 18, 1955, Serial No. 34,049

Term of patent 14 years

(Cl. D34—15)

I claim:

The ornamental design for a toy pistol or similar article, substantially as shown.
